(57) **CLAIM**

The ornamental design for a headset with modular fittings for speaking and listening, as shown and described.

DESCRIPTION

FIG. 1 is a rear view of a headset with modular fittings for speaking and listening showing my new design;

FIG. 2 is a front view thereof;
FIG. 3 is a left side view thereof;
FIG. 4 is a perspective view thereof;
FIG. 5 is a top view thereof;
FIG. 6 is a right side view thereof;
FIG. 7 is a bottom view thereof;
FIG. 8 is a left side view of a modular earpiece of the headset with modular fittings for speaking and listening of FIG. 1 shown separately for purposes of illustration;
FIG. 9 is a perspective view thereof;
FIG. 10 is a top view thereof;
FIG. 11 is a right side view thereof;
FIG. 12 is a front view thereof;
FIG. 13 is a bottom view thereof;
FIG. 14 is a left side view of the modular earpiece of the headset with modular fittings for speaking and listening of FIG. 1 shown separately for purposes of illustration;
FIG. 15 is a perspective view thereof;
FIG. 16 is a top view thereof;
FIG. 17 is a rear view thereof;
FIG. 18 is a bottom view thereof;
FIG. 19 is a front view thereof;
FIG. 20 is a right side view thereof;
FIG. 21 is a front view of the modular earpiece for the headset with modular fittings for speaking and listening of FIG. 1 shown separately for purposes of illustration;
FIG. 22 is a right side view thereof;
FIG. 23 is a rear view thereof;
FIG. 24 is a left side view thereof;
FIG. 25 is a bottom view thereof;
FIG. 26 is a top view thereof;
FIG. 27 is a front view of the modular push to talk button for the headset with modular fittings for speaking and listening of FIG. 1 shown separately for purposes of illustration;
FIG. 28 is a perspective view thereof;
FIG. 29 is a left side view thereof;
FIG. 30 is a rear view thereof;
FIG. 31 is a top view thereof;
FIG. 32 is a bottom view thereof; and,
FIG. 33 is a right side view thereof.
